UNITED STATES PATENT OFFICE

CHARLES L. MOYER, OF CHICAGO, ILLINOIS, ASSIGNOR TO QUALITY HARDWARE AND MACHINE CORPORATION, OF CHICAGO, ILLINOIS, A CORPORATION OF ILLINOIS

BOOK ASSEMBLY MACHINE

Application filed July 9, 1930. Serial No. 466,620.

This invention relates to a book assembly machine and has to do more particularly with the automatic assembly of signatures or book parts into book form for stitching purposes.

5 An object of the invention is to provide a book assembly machine of compact form and construction wherein signatures may be withdrawn from a pile, opened, deposited in open position on a signature support for delivery to a stitching machine, in a minimum amount of time.

10 Another object of the invention is to provide an assembly machine wherein the travel 15 of a signature from the pile to open position is reduced to a minimum.

15 A further object of the invention is to provide a book assembly machine for opening and accumulating signatures in open position 20 which machine may be readily adapted to open signatures of various sizes by means of a single adjustment which may be quickly made.

25 A still further object of the invention is to provide a machine wherein signatures may be withdrawn from a pile by gripper mechanisms opened and deposited in open book position without having the free edge of one of the folds of a signature extending beyond 30 the free edge of the other fold of a signature.

35 Another and still further object of the invention is to provide a book assembly machine with an inclined support for receiving signatures as withdrawn from the pile, on which support the one fold of a signature is separated from the other fold and grippers engage the other fold for moving the signature open end foremost whereby the signature 40 may be opened and deposited in open position on a signature collector.

45 A yet further object of the invention is to provide in a book assembly machine, gripper means for moving a signature for opening purposes and which gripper means engage one fold of the signature at the free edge thereof, suction means being employed to move a fold away from that engaged by the gripper mechanism prior to the time the signature is opened.

50 A still further object of the invention is

to provide an inclined support for receiving signatures as withdrawn from a pile which support is provided with means for adjusting the depth of the same to receive signatures of various sizes.

55 A yet further object of the invention is to provide, in a book assembly machine, a trough for receiving signatures from a pile and moving one fold away from the other fold by suction means and causing grippers to engage the other fold for removing the signature 60 from the support. The suction means for moving the first fold away from the other is arranged to travel with the signature as the same is delivered to the support, then away 65 from the support for moving one fold away from the other, the suction is then released and the suction means moved upwardly and then toward the support for suction engagement with the next signature delivered to the 70 support.

75 A still further object of the invention is to provide a novel pile lifting mechanism for enabling easy withdrawal of a signature from a pile.

80 Another and yet further object of the invention is to provide a mechanism for reversing the direction of travel of a signature withdrawn from a pile by gripper means, and moving the signature by gripper means open end foremost with the gripper means engaging same fold of the signature and clamping the other fold to direct the same over a signature collector.

85 The above, other and further objects of the invention will be apparent from the following description, accompanying drawings and appended claims.

90 Generally speaking, the machine contemplates the withdrawal of a signature from a pile folded end foremost, then delivering the same to an inclined support where suction means engage a fold of the signature adjacent its free edge and then moves the engaged edge away from the other to enable 95 gripping of the other edge by gripper means, suction then being released and the signature withdrawn from the support by the other gripper means with the gripped fold directed in a curved path and the free fold crimped 100

substantially tangentially to the gripped fold for delivery in open position onto a signature collector. The invention further contemplates a novel pile lifting mechanism 5 operated in timed relation to the signature withdrawing means to enable easy withdrawal of the bottommost signature of a pile.

The invention further contemplates the provision of an inclined support for receiving 10 the signature from the withdrawing grippers and there separating one fold from the other folds to enable engagement of the other fold by additional gripper means for removing the signature from the support. 15 The suction opening means at the support is arranged to travel with and with respect to the signature for opening purposes.

An embodiment of the invention is illustrated in the accompanying drawings and the 20 views thereof are as follows:

Figure 1 is an end elevation of a machine embodying the present invention.

Figure 2 is a transverse sectional view through the illustrated form of machine 25 taken substantially in the plane of line II—II of Figure 5.

Figure 3 is a fragmental front elevation of the machine taken substantially in the plane of line III—III of Figure 1.

30 Figure 4 is a fragmental top plan view of the illustrated form of machine.

Figure 5 is a top plan view, partially in section, of the illustrated form of the machine, with the signature box removed.

35 Figure 6 is an end view of the cams, levers and associated parts of the pile raising mechanism and the signature deflecting mechanism, with the parts shown immediately prior to the commencement of the deflecting movement.

40 Figure 7 is a view similar to Figure 6 showing a signature deflected from the pile and the foot of the pile lifter underneath the front of the pile ready for raising the same.

45 Figure 8 is an elevational view of the cams, levers and associated parts for controlling the suction operation of the suction means for opening a signature on the inclined support, showing the signature opened by the suction means and grippers about to engage the free edge of the other fold of the signature.

50 Figure 9 is an elevational view of the cams, levers and associated parts for controlling the suction supply to the deflecting suction cups at the piles.

55 Figure 10 is an elevational view of the cams, levers and associated parts for actuating the movement of the suction separating means, with the parts showing the suction means at the lower end of its path of movement.

60 Figure 11 is similar to Figure 10 showing

the parts with the suction means at the top of the path of movement.

Figure 12 is an enlarged fragmental view showing the cams, levers and associated parts as the same appear in Figure 10, which view is taken behind the parts as shown in Figure 10.

Figure 13 is a view similar to Figure 12 of the position of the parts illustrated in Figure 11.

Figure 14 is an elevational view of a tumbler and associated mechanism employed for actuating the gripper fingers on the gripper wheels.

Figure 15 is a sectional view taken on line XV—XV of Figure 16 and shows the illustrated form of means for imparting to and fro movement to the deflecting suction cups and associated parts.

Figure 16 is a section view taken on line XVI—XVI of Figure 15, showing details of construction and relation of certain of the parts.

The form of machine selected to exemplify the present invention is illustrated as having 65 end members A and B of cast metal. There may be intermediate members similar to the end members if the length of the machine is such as to justify the same.

The length of the machine, that is the distance between the end members A and B, may be increased or decreased as occasion requires and as determined by the amount of work to be done on the same.

The machine is illustrated as supported on 100 legs 1 which may be of wood or other suitable material.

A table C is provided as a support for piles of signatures. There may be as many piles of signatures along the table C as may be 105 readily accommodated, taking into consideration the length of the table C and the sizes of the signatures.

Signature deflecting mechanism

110 The bottommost signature of every pile is deflected by suction means referred to herein as suction cups.

A suction pipe 2 extends along the front of the table C and has communicating therewith at intervals in the length thereof branches 3 which terminate in cups 4. The pipe 2 is supported at its end in brackets 5 which are pivoted to pins 6 carried in the adjacent end members of the machine. The pins 6 are carried in the brackets 5 which brackets have slides 13 for inward and outward movement with respect to the signature table C i. e. movement of translation.

An arm 7 extends from the brackets 5 and pipe 2 thereof and carries a roller 8 for engagement with a cam 9 (Figures 6 and 7) for oscillating the arm and its attached bracket 5.

Secured to each of the pins 6 is a gear 10 meshing with gear 11 fastened to the pipe 2.

A rack bar 12 is fastened to the frame of the machine.

The suction cups 4 are spaced from the front edge of the signature support C for 5 suction engagement with the lowermost signature in a pile to deflect the same from the pile into position to be gripped by the gripper mechanism for withdrawing the signature from the pile.

10 It has been found that when the cups 4 are spaced from the front edge of the signature support C, it is necessary that the cups in moving downwardly for deflecting the lowermost signature should also move inwardly 15 toward the signature support in order to prevent tearing of the signature or breaking of the suction.

The present arrangement of the suction deflecting means enables downward and inward 20 movement of the suction cups 4.

The arm 7 following the cam 9 on swinging downwardly will cause the brackets 5 to swing about its pivotal support 6. The gears 10 and 11 during such movement will 25 cause inward movement of the slide portion 13 of the bracket as rotation of the pipe 2 will tend to turn the gear 10 and cause it to travel inwardly on the rack bar 12. Such construction therefore causes the center of 30 the cups 4 to follow an arcuate path from the front edge of the signature board C with a radius from such front edge to the center of the cups. Such path of movement is indicated as a curved line 14 of Figure 15.

35 The cam 9 is affixed to a shaft 15 supported in journals 16 of the end members A and B.

The pipe 2 is connected to a valve 17 (Figure 9) which controls suction through the pipe. A valve stem 18 extends from the valve 40 body and rests against an arm 19 of a bell crank D which is pivoted at 20 to the end member B. The other arm 21 of the bell crank is connected at 22 to a lever 23. The lever 23 has its other end provided with 45 spaced ends 24 resting on a bushing 25 on the shaft 15. A cam 26 is secured to the shaft 15 which engages a roller 27 on the lever 23 for moving the same backwardly and forwardly to open and close the valve 17 in the 50 suction line 2.

Pile lifting means

An angle member 28 extends along the upper portion of the machine from end to end 55 thereof and supports blocks 29 which are fastened thereto by bolts 30. A rock shaft 31 is carried in the blocks 29.

A series of blocks 32 secured to the horizontal member of the angle 28 support a 60 shaft 33 which is parallel to the shaft 31 and illustrated as below the same.

Brackets 34 are arranged on the shaft 33 for rocking movement and are provided with upstanding ears 35. Cranks 36 are secured 65 to the rock shaft 31 for movement therewith

and at the other ends are connected by links 37 to the ears 35 of the brackets 34 for rocking the brackets about the shaft 33 whenever the rock shaft 31 is actuated. The brackets 34 are also provided with apertures vertically 70 disposed for receiving rack bars 38 with the bars arranged one to an aperture. The rack bars 38 slide in the apertures of the brackets 34 in a manner to be presently described.

Gears 39 are keyed to the shaft 33 and 75 mesh with rack bars 38 so that when the gears are rotated in either direction, the rack bars will be raised or lowered, as the case may be. The lower ends of the rack bars 38 are provided with laterally extending feet 40 which 80 under certain conditions engage under the front edge of the piles to raise the same.

A crank arm 41 is fastened to the rock shaft 31 and also to a lever 42. The lever 42 has its other end provided with extensions which 85 rest on a bushing 43 on the shaft 15. A cam 44 keyed to the shaft 15 engages a roller 45 secured to the lever 42 for imparting to and fro movement thereto for the purpose of rocking the shaft 31.

90 Another lever 46 has one end provided with parallel spaced extensions 47 engaging the bushing 43. The other end of the lever 46 is connected to a crank 48 which is keyed to the rock shaft 33. Movement is imparted to 95 the lever 46 by a cam 49 on the shaft 15 cooperating with a roller 50 on the arm 46.

The cams 44 and 49 are so designed that if rotation is imparted to the shaft 15 in the manner to be hereinafter explained, said 100 cams will cause to and fro movement of the levers 42 and 46, rocking the shafts 31 and 33, respectively. The rock shaft 33 imparts oscillatory movement to the gears 39 thereon while rocking the shaft 31 moves the brackets 34 about the shaft 33 as a center so as to swing the rack bars 38 away from against the folded edges of the signatures on the table C as may be observed in dotted lines in Figure 6.

110 The parts above described cause swinging movement of the rack bars 38 about the rock shaft 33 as a center and also longitudinal movement of the bars in order that the piles of signatures on the table C may be raised at 115 the proper moment and also in order that the rack bars 38 may be moved away from the exposed edges of the signatures in the pile to enable the suction cups 4 to engage against the under side of the lowermost signature for deflecting the same and when deflected, the rack bars are swung into such position that the lateral extensions 40 will then engage against the next but one of the lattermost signatures in order that the pile may be raised when 120 the racks 38 are elevated.

Gripper withdrawing means

Gripper means are provided for withdrawing signatures from the piles of signatures 130

on the table C and as illustrated, this means includes a plurality of gripper wheels 51 keyed to the shaft 15 and arranged at intervals along the front of the table C. A rod 52 passes through all of the gripper wheels between the shaft 15 and the periphery of the wheels and carries fingers 53 which are arranged to engage against lateral extensions 54 adjacent the sides of the peripheries of the wheels. The rod 52 is rocked by a tumbler, such for instance as that illustrated in Figure 14. A circular disk 55 is secured in position at either end of the machine as desired, for actuating the rod 52. The disk 55 in the illustrated form of the apparatus is shown attached to the end wall B (Figure 3) and has attached to it two arcuate flanges 56 and 57, the flange 56 extending laterally from the periphery of the disk and the flange 57 spaced inwardly of the disk.

A frame member 58 is keyed or otherwise fastened to the end of the rod 52 adjacent the plate 55 and carries two rollers 59 and 60. Observing the arrangement of parts as illustrated in Figure 14, the bracket 58 attached to the rod 52 is movable clockwise and the roller 59 engaging the end of the flange 56 is tilted so as to rock the rod 52 about the roller so that the bracket then assumes the position shown in dotted lines in said figure. This is the arrangement of the bracket and the roller when the gripping fingers 53 are in gripping position. The bracket 58 and its roller move with the rod 52 as the shaft 15 is rotated. As soon as the roller 59 reaches the end of the flange 56, the weight of the part will tend to move the bracket sufficiently so that the fingers 53 release engagement with the signature. Continued rotation of the shaft 15 then brings the bracket to the second dotted line position whereupon the roller 60 which is then in advance will strike the end of the flange 57 and the bracket 58 will turn the rod 52 to the position shown in full lines in Figure 14 which is the open position of the fingers.

Inclined support

Castings 60 and 61 are secured adjacent the end walls of the machine and have the faces 62 thereof inclined downwardly from front to rear. Each of these castings supports a rack bar 63 meshing with gear 64 carried on a shaft 65 which extends from side to side or end to end of the machine. A hand wheel 66 is secured to the shaft 65 for rotating it in either direction to move the rack bar 63 up or down as the case may be. A flat member 67 is connected to each of the rack bars 63 lengthwise of the machine and is provided at intervals in its length with pins 68 which extend normal to the surface of the member 67.

A plurality of loops of metal strips 69 are secured to the framework of the machine from end to end thereof and in spaced rela-

tion to serve as an open cage-like trough. These loops are formed with the bend at the lower end and with the upper or free end spaced. The end 70 of the inner side of the loop extends above the other end and is vertical to serve as a guide during the time that a signature is being discharged into the inclined member from the withdrawing grippers.

The pins 68 serve as the bottoms of the inclined ports or troughs and may be adjusted up and down by manipulation of the shaft 65 operating the rack bar 63 in a desired direction. This particular adjustment to which the shaft 65 enables adjustment of the inclined port or trough to accommodate signatures of any size desired.

Inclination of the castings 60 and 61, and of the loop 69 may be as desired to accomplish the desired results.

Opening gripper arrangement

A shaft 71 is supported in the end members of the machine and is provided with a plurality of gripper wheels 72 which are similar in all respects to the gripper wheels 51 heretofore described. A rod 73 extends through the gripper wheels 72 and carries the gripper finger 74. This rod 73 is actuated by a tumbler in the same manner as described with respect to the actuation of the rod 52.

Suction opening means

A signature delivered to the inclined support is opened by suction means engaging one fold of the signature near the free edge thereof to enable the finger 74 of the gripper wheels 72 to have gripping engagement with the free edge of the other fold of the signature or withdrawing it from the inclined support and moving it into opening position.

Figure 2 illustrates a signature on the inclined support having one fold thereof moved away from the other fold by suction means.

The suction means will for convenience be referred to herein and described as suction tubes to distinguish over the suction cups 4 utilized for deflecting the lowermost signatures of the piles.

Rock shafts 75 and 76 are journaled at 77 and 78, respectively, in the end members of the machine and extend from end to end of the same. A plurality of suction tubes 79 arranged at intervals from end to end of the machine are supported in brackets 80.

Attached to rock shaft 75 are cranks 81 which are connected at 82 to a link 83, the other end of which is pivoted at 84 to a link 85 of which the brackets 80 forms a part. A crank 86 is keyed to the rock shaft 76 and is pivoted at 87 to the link 85.

A suction pipe 88 is secured in the end members and flexible connectors 89 in engagement with the interior of the pipe 88 with the several suction tubes 79.

5 A valve 90 is inserted in the suction pipe 88 and its valve stem 91 is actuated by an arm 92 of a bell crank E pivoted at 93 to the framework of the machine. The other arm 94 of the bell crank is pivoted to a lever 95 which is given to and fro motion by a cam 96 on the shaft 71. The lever 95 has its ends separated and provided with extensions 97 for engaging a bushing 98 on the shaft 71.

10 A stub shaft 99 is secured inwardly of the end wall E of the machine and is interposed between the shafts 15 and 71.

15 Rocking the shaft 75 imparts sideways movement to the suction tubes 79. Rocking the shaft 76 raises and lowers the suction tubes 79.

The tubes 79 move in a definite path while the machine is in operation, movement of the tubes being as follows:

20 Referring to Figure 2 which is the bottom outward position of the tubes, it is then next moved to the left, then upwardly to its upper limit of travel which is that shown in Figure 11, then to the right and downwardly. Such movement of the tubes moving with the signature after having made suctional engagement with the same downwardly and then its movement to the left moves one fold of the signature away from the other to enable gripping of the other fold by the fingers 74 on the wheels 72. Suction is then released, the tubes 79 move upwardly, then forwardly for making suctional engagement with the next signature.

35 A rocker member 100 is keyed to rock shaft 75. One end of a lever 101 is pivoted at 102 to the member 100. The other end of the lever is provided with spaced extensions 103 which engage a bushing 104 on the stub shaft 99. A cam 105 is keyed to shaft 99 and engages against a roller 106 supported on the inner side of the lever 101.

40 A crank 107 is keyed to the rock shaft 76 and has pivoted thereto a lever 108 which at its other end has extensions 109 resting on the bushing 104 of the shaft 99. A cam 110 is keyed to the shaft 99 and engages a roller 111 on the inner side of the lever 108. Thus as the shaft 99 is rotated in a manner 45 to be presently described, the levers 101 and 108 rock the shafts 75 and 76 by moving the suction tubes 79 through the path heretofore described.

Kicker mechanism

55 Provision is made to return the one side of the signature separated from the other side by the suction tubes so that the signature may be withdrawn from the inclined support.

60 Such mechanism consists of a rocker shaft 112 to which is attached brackets 113 carrying upstanding strips 114 which strips are placed between the loops 69. A crank 115 is secured to one end of the rock shaft 112 and

is oscillated by means of a lever 116 pivoted to the crank at 117 which lever in turn has its other end provided with spaced extensions 118 engaging bushing 98 on the shaft 71. A cam 118 is fixed to shaft 71 engages a roller 119 on the lever 116 to reciprocate the same.

65 It will thus be observed that as the lever 116 is reciprocated, the strips 114 will be kicked toward the one side of the signature engaging the same and thereby pushed toward the other sides of the signature with the free edges of the signature lying against the top sides of the gripper fingers of the gripper wheels 72.

Driving mechanism

80

The apparatus is driven from a suitable source of power through a shaft 120 journaled at 121 to the end member A of the machine. A bevel gear 122 is keyed to the shaft 120 and meshes with a bevel gear 123 keyed to the shaft 71. Any suitable source of power may be applied to the shaft 120 or driving the machine.

70 Tie rods 124, 125 and 126 are provided extending from end to end of the machine and suitably secured in the end members of the same.

75 Rollers 127 carried on brackets 128 are provided so that the surfaces of the rollers 127 contact with surfaces of the gripper wheels 72.

80 Guide members 128 overlying the gripper wheels 172 are provided at intervals from end to end of the machine so that as the signatures are being raised from the inclined supports, the free fold thereof will be directed between the gripper wheels 72 and the rollers 127 for opening purposes.

85 A plurality of crimpers 129 are secured to the machine between the ends thereof for crimping the free folds of the various signatures being held between the gripper wheels 72 and rollers 127. Crimpers are shown in the present instance as supported from the tie rods 126. These crimpers crimp the free fold of the signature thus stiffening the same to direct the same outwardly away from the gripper wheels 72 as the same are moving in clockwise direction with the other fold of the signature gripped by the fingers 74 of these wheels. The crimpers tend to buckle the one fold of the signatures to direct the same over the saddles 130 on which the signatures are collected in open position and from which saddles the collected signatures are removed by chains or similar means in the usual manner.

90 A gear 131 is secured to shaft 15. Another gear 132 is fastened to shaft 71. A gear 133 is carried on the stub shaft 99 and meshes with gears 131 and 132. Rotation therefore of the shaft 71 by the driving shaft 120 rotates the shafts 15 and 71 in the same direction.

105

110

115

120

125

130

A pile of signatures G is placed on a signature table C folded ends to front. There may be as many piles of signatures as the length of the table will accommodate, depending of course on the size of the signatures. Fixed at intervals are signature guides 134 which are spaced from the front edge of the table C to serve as abutments when signatures are placed on the table. The guides 134 consequently limit the projection of the signatures beyond the front edge of the table C thereby maintaining these in proper position to be engaged successively by the vacuum cups 4 for deflecting purposes.

The machine from end wall to end wall may be as long or as short as desired and may be designed to open one pile of signatures or many piles of signatures. There are provided several of the suction cups 4, the withdrawing gripper wheels 51, the opening gripper wheels 52 while the inclined support or trough extends from end to end of the machine. The various instrumentalities heretofore described may be arranged in multiple units, and a unit would be actuated in the manner described as to the various elements and combination of elements.

The operation of the machine is as follows:

The position of parts at the time the machine is ready for operation is such that the suction cups 4 are in up position, that is with the top face of the cups in alignment with the table C as is shown in Figures 6 and 15 of the drawings. The cups 4 support the extending edges of the piles of signatures on the table C until the cups are moved downwardly for deflecting purposes.

The pile raising mechanism is as shown in Figure 6, that is with the rack 38 down with the lower end thereof tilted away from the piles.

Immediately on commencement of operation of the machine, the timing of the various cams, levers and the like is such that the suction pipe 2 is opened to the source of suction resulting in the creation of suction at the cups, thereby deflecting the lowermost signatures in the piles. The rotation of the shaft 15 with its rotation of cams 9 causes the swinging downwardly of the cups 4 with the consequent inward movement of the brackets supporting the pipe 2 and the cups 4. Thus the cups move downwardly carrying with the same the deflected edges of the signatures, deflecting such signatures in a curved path the center of which is the front edge of the table B and the radius of which is the distance from the front edge of the table to the center of the cups as the same is moved downwardly and inwardly.

As soon as the lowermost signatures have been deflected sufficiently, the gripper fingers 53 of the gripper wheels 51 close against the

folded edges of the deflected signatures and the suction in the pipe 2 is shut off so that the signatures are no longer held by the suction cups but are free to move with respect to the same whereupon the gripper wheels 51 rotating in clockwise direction as viewed in the figures in the drawings with the signatures from the bottoms of the several piles. A signature so withdrawn is carried in a circular path until the folded edge is over the inclined support or trough whereupon the tumbler mechanism of Figure 14 is actuated to open the fingers 53 thereupon releasing engagement with the signature whereby the same drops into the trough.

In the meantime, the suction tubes 79 have been moved upwardly to the position of Figure 11 and as the signatures drop into the trough, move forwardly and suction is established in the pipes 88 and the various suction tubes 79. This action results in the adjacent folds of the signatures being held against the tubes 79 and as these tubes travel downwardly with the signatures dropping into the trough until the bottom is reached, then moved inwardly that is away from the trough in the manner illustrated in Figure 2 thus separating one fold from the other.

The parts are so arranged and timed that as the signatures reach the bottom of the trough, that is, against the pins 68, the gripper fingers 74 of the gripper wheels 72 engage the free edge of the other fold of the signature and withdraws the signature from the trough. At this time, or immediately before, suction in the tubes 79 has been cut off and the kicker shaft 112 actuated so that the one fold of the signature is kicked against the other fold with the free edge thereof on top of the finger 74 of the gripper wheels 72. Thus the signatures are withdrawn from the trough. Guides 128 serve to direct the free fold of the signature along with the gripped folds between the gripper wheels 72 and rollers 127.

The crimpers 129 then become effective to stiffen the free fold of the signatures and extend the same substantially tangentially to the path of movement of the gripped folds, that is over the saddles 130 or collecting supports. This free fold of the signature is maintained stiffened until it is over the saddle or support 130 whereupon the gripper fingers 74 are released from gripping engagement allowing the opened signature to fall onto the saddles or supports 130 whence the same are collected in the usual manner for delivery to a stitching machine.

There are provided directing rollers 135 carried on arms 136 supported on a tie rod 137 engaged on the various gripper wheels 72 and disposed a slight distance above the inclined support to aid in guiding the one fold of the signature that is the free fold against the guides 128.

The apparatus of this invention may be

made as a unit, that is with one set of gripper wheels 51 and 72 and one pile raising mechanism or may be made as a combination of units in which event there would be a pile raising means for each of such units or if desired, there may be used several pile raising means if perchance the piles of signatures are heavy or the signatures large. The fact that but one pile raising mechanism as illustrated in Figure 4 is not to be construed against applicant as there are utilized as many of these pile raising mechanisms as there are piles on the table C. However, applicant has not illustrated all of these as it might lead to some confusion in the drawings.

There are of course as many sets of suction tubes 79 as there are piles of signatures as it is essential that all of the signatures delivered onto the inclined support be opened to enable gripping by the gripper wheels 72 for inversion and opening before deposited on the collectors. Preferably, there are at least two of the suction tubes 79 per signature. Figure 5 shows connection for a plurality of such tubes.

The invention has been described herein more or less precisely as to details, yet it is to be understood that the invention is not to be limited thereby, as changes may be made in the arrangement and proportion of parts and equivalents may be substituted without departing from the spirit and scope of the invention.

The invention is claimed as follows:

1. A book assembly machine, in combination, suction means for deflecting a signature from a pile, pile lifting mechanism, gripper wheels having grippers thereon for engaging said deflected signature, an inclined support disposed to receive a signature released by said grippers, suction tubes bodily movable up and down adjacent the inclined support, a suction line for said tubes, means for moving said tubes against a signature and opening said tubes to the suction line as said signature nears the bottom of said inclined support, said tube moving means then effective to move said tubes and the fold of the signature in engagement therewith away from the other fold of the signature, grippers engageable with the other fold of the signature for moving the signature upwardly and away from the support, a guide for directing the free fold of said signature along with the gripped fold, a crimper engaging said signature for crimping the free fold thereof to stiffen the same as said gripped part is moved by said grippers in a substantially circular path, a saddle adjacent said machine, and said grippers releasing said signature when said stiffened fold thereof has been moved to overlie said saddle.

2. A book assembly machine including in combination, suction means for deflecting a signature from a pile, gripper means for

withdrawing the deflected signature, an inclined support for receiving said signature when released by said grippers, suction means engaging one fold of a signature to open the same while on said support, gripper means engaging the other fold of a signature and withdrawing the same from said support, means for crimping the ungripped fold of a signature, a signature collector, and said last gripping means releasing said signature when said crimped fold has been moved over said collector.

3. A book assembly machine including in combination, pile lifting mechanism, gripper wheels having gripper fingers thereon for withdrawing a signature from a pile, a tumbler for actuating said fingers, a downwardly extending trough to receive a signature when released by said grippers, suction means engaging the fold of a signature to open the same while in said trough, gripper means engaging the other fold of a signature and withdrawing the same from said trough, a crimper engaging said signature for crimping the free fold thereof to stiffen the same as said gripped part is moved by said grippers in a substantially circular path, a saddle underlying said opened signature, and said grippers releasing said signature when said stiffened part thereof is over said saddle.

4. A book assembly machine including in combination, suction means for deflecting a signature from a pile, said suction means having movement of translation toward and away from said pile, said suction means being swingable downwardly from the pile, means for effecting the aforesaid movement of said suction means, and cam actuated means for operating said last mentioned means.

5. A book assembly machine including in combination, suction means for deflecting a signature from a pile, said suction means being movable toward and away from said pile, said suction means being swingable downwardly from the pile, rack and pinion for effecting the aforesaid movement of said suction means, cam actuated means for operating said rack and pinion, cam actuated means for controlling suction to said suction means, a valve in the suction line, an oscillating arm for actuating said valve, a cam for oscillating said arm, and all of said means being operable in sequential relation.

6. A book assembly machine including in combination, means for deflecting a signature from a pile, pile lifting mechanism, said mechanism including an L-shaped member having a rack thereon, a gear meshing with said rack, a rock shaft, connections between said rock shaft and said member for tilting said member, an oscillating shaft, connections between said oscillating shaft and said gear for oscillating said gear to raise and lower said member, said member having a sliding support, and connections between the

pile lifting mechanism and the means for deflecting a signature for moving the same in timed and sequential relation.

7. A book assembly machine including in combination, means for deflecting a signature from a pile, an inclined support disposed to receive a signature withdrawn from said pile, means for adjusting the depth of said inclined support, said means including a bar and pins on said bar projecting into said inclined support and means for adjusting said bar.

8. A book assembly machine including in combination, means for deflecting a signature from a pile, gripper means for withdrawing a deflected signature, an inclined support for receiving a signature when released by said grippers, suction tubes bodily movable up and down for suction engagement with a fold of a signature in said support, and means for moving said tubes in the manner stated.

9. A book assembly machine including in combination, means for deflecting a signature from a pile, gripper means for withdrawing a deflected signature, an inclined support for receiving a signature when released by said grippers, suction tubes bodily movable up and down for suction engagement with a fold of a signature in said support, means for moving said tubes in the manner stated, a suction supply pipe communicating with said tubes, a cam actuated valve in said supply pipe, and said cams for moving said tubes being arranged in timed relation with said gripper means as to move said tubes against a signature and open said tubes to the suction line as a signature nears the bottom of the support after release by the grippers.

10. A book assembly machine including in combination, means for deflecting a signature from a pile, gripper means for withdrawing a deflected signature, an inclined support for receiving a signature when released by said grippers, suction tubes bodily movable up and down for suction engagement with a fold of a signature in said support, means for moving said tubes in the manner stated, said tube moving means being effective to move said tubes and the fold of the signature in engagement therewith away from the other fold of the signature.

11. A book assembly machine including in combination, means for deflecting a signature from a pile, gripper means for withdrawing a deflected signature, an inclined support for receiving a signature when released by said grippers, suction tubes bodily movable up and down for suction engagement with a fold of a signature in said support, means for moving said tubes in the manner stated, a suction supply pipe communicating with said tubes, a cam actuated valve in said supply pipe, and said cams for

moving said tubes arranged in timed relation with said gripper means as to move said tubes against a signature and open said tubes to the suction line as a signature nears the bottom of the support after release by the grippers, said tube moving means being effective to move said tubes and the fold of the signature in engagement therewith away from the other fold of the signature.

12. A book assembly machine including in combination, suction means for deflecting a signature from a pile, means for raising the pile away from a deflected signature, gripper means engageable with such deflected signature for withdrawing the same from the pile, a trough for receiving said signature from said grippers, a suction tube engageable with one fold of said signature as the same enters said trough and moving said engaged fold away from the other fold of the signature, gripper means engaging the other fold of the signature, connections between the suction control means and gripper actuating means to release the suction as said grippers engage said other fold of the signature, a pusher for moving said first fold of the signature against the other fold after release therefrom by said suction tube, a guide for directing said first fold in the same path of travel as the gripped fold, an arm engaging the signature for crimping the ungripped fold thereof to stiffen said fold as the signature is moved by said grippers, and a support for receiving said opened signature.

13. A book assembly machine including in combination, suction means for deflecting a signature from a pile, gripper means for withdrawing a deflected signature, a trough for receiving said signature when released by said grippers, suction means engaging one fold of the signature in the trough to open the signature, gripper means engaging the other fold of said signature and withdrawing the same from the trough, means for crimping the ungripped fold of the signature, a saddle, and said last gripping means releasing said signature when said crimped fold has been moved over said saddle.

14. A book assembly machine including in combination, revolving means for withdrawing a signature from a pile, means for opening a signature, said opening means including suction means engaging one fold of a signature and moving said fold away from the other fold thereof, revolving gripper means for engaging said other fold of said first fold and away therefrom, said suction means then freeing said first fold, and crimping means engaging said free fold for stiffening the same to move away from said gripped fold while the same is being moved by the last mentioned revolving means.

15. A book assembly machine including in combination, revolving means for withdraw-

ing a signature from a pile, means for opening the signatures, said means including suction means temporarily engaging one fold of a signature and revolving gripper means engaging the other fold of the signature, a support for receiving open signatures, and said gripper means delivering said signatures to said support in open position.

16. A book assembly machine including, an inclined support down which signatures are fed folded end foremost, means for separating one fold of the signature from the other while the signature is on said support, rotating gripper means engaging said other fold and withdrawing the signature from said support open end foremost, means positioning said one fold and separating the same from said other fold, and a support on which the opened signature is deposited when said grippers release said other fold.

17. A book assembly machine including, an inclined support down which signatures are fed folded end foremost, suction means for separating one fold of the signature from the other fold while said signature is on said support, rotary grippers engaging said other fold and withdrawing the signature from said support open end foremost, means for buckling said one fold and separating the same from said other fold, means directing said one fold into position to be buckled, and a support on which the opened signature is deposited when said grippers release said other fold.

18. A book assembly machine including, an inclined support down which signatures are fed folded end foremost, adjustable stops for limiting the extent of travel of signatures along said support, means for separating one fold of a signature from the other fold while said signature is on said support, rotary grippers engaging said other fold and withdrawing said signature from said support open end foremost, and means buckling said one fold and separating the same from the other fold as said signature is withdrawn from said support.

In testimony whereof I have hereunto subscribed my name at Chicago, Cook County, Illinois.

CHARLES L. MOYER.
